(57) CLAIM

The ornamental design for a nonwoven fabric with surface pattern, as shown and described.

DESCRIPTION

FIG. 1 is a top plan view of a nonwoven fabric with surface pattern; and,

FIG. 2 is an enlarged detail view of the area 2 circumscribed by broken lines within FIG. 1.

The broken line surrounding FIG. 1 depicts the boundaries of the claim and forms no part thereof. The broken line within FIG. 1 and surrounding FIG. 2 depicts the boundaries of the detail area and forms no part of the claimed design.

1 Claim, 2 Drawing Sheets(56)
